UNITED STATES PATENT OFFICE.

JAMES A. TAYLOR, OF GLEN RIDGE, NEW JERSEY.

RIVET BRACE.

Application filed November 18, 1918. Serial No. 262,081.

To all whom it may concern:

Be it known that I, JAMES A. TAYLOR, a citizen of the United States, residing at the borough of Glen Ridge, county of Essex, State of New Jersey, have invented new and useful Improvements in Rivet Braces, of which the following is a specification.

The process of riveting requires that a firm brace be placed behind the head of a rivet to keep the same rigidly in the rivet hole while the end furthest from the head is being hammered down. For this purpose the brace behind the rivet should be rigid and unyielding. The method of bracing usually in vogue consists of a heavy steel hammer held in place back of the rivet by a workman. This method has many disadvantages and the hammer is driven back by the blows of the riveting tool and this movement permits an element of play in the rivet and prevents the rivet being driven tightly and snugly, and, in addition, much power is lost by being transmitted to the movable hammer. A blow delivered to a solid rivet shaft would spread the shaft at all parts and thus would fill the rivet hole quickly instead of at the end of the process when the rivet is cold, for the reason that the movement of the rivet back and forth prevents its parts being wedged into the irregularities of the face of the rivet hole. The process calls for great strength by the holder-on, who inevitably becomes tired and slows up and since he is the man who inserts the rivet, he is the one who sets the pace and if he is tired and slows up he wastes the time of the other three or four men in the "gang" which in the aggregate is a very serious matter. In any event, there is a serious loss of time because the "holder-on" must do all his acts in succession and is unable to proceed to a second operation while any other is being performed.

The objects of my invention are to provide a device which will aid in all the operations of bracing a rivet while the same is being driven by providing a mechanical brace, which will hold the rivet firmly in place without physical assistance by the holder-on and which can be locked in place. By providing a plurality of braces on the same brace bar, a plurality of rivets can be braced at the same time and locked in position. In this way a hot rivet is always ready for the riveter, who is the most highly paid member of the gang and whose time

is conserved to the utmost. The freedom from jar and exhaustion on the part of the "holder-on" enables him to work continuously at uniform speed without tiring.

To such ends my said invention, in its preferred form, consists of a brace bar attached by adjustable plugs to the material to be riveted together, a movable, sliding collar mounted on this brace bar supporting a movable brace part and means for changing the position to such brace part comprising a cam part, a ratchet locking part in connection with the cam part by means of a stiff coil opening and a lever for actuating the ratchet part and a pawl for locking the same in position. The ends of the brace bar are provided with slots into which fit the securing plugs and by reason of which slots the plugs have considerable latitude of movement to allow being inserted into rivet holes placed in regular positions.

My said invention is fully shown, described and claimed in the following specification of which the accompanying drawings form a part; wherein letters or numerals of reference designate like or equivalent parts wherever found throughout the several views and in which:

Figure 1 is a top view of the entire device showing the brace bar secured to the material to be riveted together and in relation to the rivet holes, the sliding collar on the rivet bar supporting a brace part, means for changing the position of the brace part and for locking the same in position.

Figure 2 is a top view in detail of the movable sliding collar supporting the rivet brace, the cam part (in dotted lines) for changing the position of the rivet brace, the locking cam-actuating part with the lever and spring for actuating and the ratchet and pawl for locking the same and the cam part in position and the set screw for securing the movable collar on the brace bar in operative position.

Figure 3 is a side view in detail of the movable sliding collar supporting the rivet brace, the cam part for changing the position of the latter, the locking part with the lever and spring for actuating and the ratchet and pawl for locking the same and the cam part in position, the set screw for securing the movable collar on the brace bar and showing the brace bar in cross section.

Figure 4 is an end view in detail of the movable sliding collar, supporting the rivet

- brace, the cam part for changing the position of the rivet brace, the locking part with the lever and spring for actuating the cam part and the ratchet and pawl for locking the same in position, the bar connecting the cam part and the rivet brace and showing in dotted lines the position taken by the cam part, the rivet brace, and the connecting bar when at the limit of motion.
- 10 Figure 5 is a side view of the rivet brace part.
- Figure 6 is a front side view of the brace bar provided with plugs for securing the same to the material to be riveted together.
- 15 Figure 7 is a side view in detail of one of the plugs for securing the device to the material to be riveted together, showing the shaft projecting parts above and below the end of the brace bar and the projecting part at the lower end of the plug, the wedge locking part for forcing the projecting part beneath the material to be riveted together and the spring for keeping the same in position, and showing in dotted lines the position taken by the plug and the wedge part when in locked position, all of which are shown in their relation to a rivet hole and the material to be riveted together and the end of the brace bar.
- 20 25 Figure 8 is a top view of the wedge locking part and of the securing plug with the projecting part at the lower end and showing in cross section along the line $a-a$ of Figure 7, the shaft of the securing plug and in full lines the top of the rod for actuating the locking part.

Figure 9 is a side view of one of the ends of the brace bar showing the means for elevating the main part of the brace bar above the material to be riveted together and the plug for securing the bar to such material, partly in detail.

My said new and improved rivet brace comprises a brace bar A, Figs. 1, 3 and 6 on which is movably mounted a sliding collar B, Figs. 1, 2, 3 and 4, which supports a brace C for holding a rivet firmly in place while the same is being driven by tool held on the opposite side of the material to be riveted together.

The rivet brace C is movably mounted on the collar B by means of the bar 1, Figs. 2, 3, 4 and 5 passing through an aperture in the collar B. The downward movement of the brace C is limited by the cap 2 on the bar 1.

The brace C is provided with a strengthening part 3, Figs. 2, 3, 4, and 5, the inner face 4, Figs. 2, 3 and 5, of which abuts against the outer face of the collar B. The part 3 serves to strengthen the brace C and to distribute the force of the riveting blow.

Loosely pivoted at the end of the collar B by the bolt 5, Figs. 2, 3 and 4 is the cam part 65 D having an egg or ovoidal shaped perim-

eter, the horizontal diameter of which in the normal position is greater than the vertical diameter. The upper face of the cam part D abuts against the under face of a horizontal projection 6 on the collar B, Figs. 3 and 4. The under face of the cam part D abuts against the upper face 7, Figs. 3 and 4 of the brace C.

Pivoted to the bolt 5, Figs. 1, 2, 3 and 4, adjacent to and outside of, the cam part D is the locking part E, whose right outer edge is concentric with the corresponding edge of the cam part D and is provided with a ratchet 8, Figs. 1, 2, 3 and 4. Secured to the face opposite the ratchet face of the part E is the bar 9, Figs. 2, and 4, which passes through an aperture slightly larger than the bar 9 in a projection 10 of the cam part D and which is fitted at its outer end with a cap 11 which is larger than the aperture in the projection 10. Around the bar 9, Figs. 2 and 4, is placed a stiff coil spring 12 between the projection 10 and the face of the part E. Secured to the collar B by the bolt 13, Figs. 2, 3 and 4, is the pawl 14, which is kept in engagement with the ratchet 8 by the pressure of the flat spring 15, Figs. 2 and 3, on its upper face. Secured to the part E, Figs. 1, 2, 3 and 4, is the lever 16 which is held in a vertical position when the part E is in normal and non-operative position. When the lever 16 is moved to the left and downward Fig. 4, (as shown in dotted lines) the part E is rotated on the pivot 5 to the left and the face of the same presses against the coil spring 15 which is in turn forced against the projection 10 on the cam part D. This pressure causes the cam part D to rotate on the bolt 5 and this rotation brings into contact with the face 7 of the brace C, Fig. 4, portions of the lower face of the cam part D which are continuously further and further removed from the pivot 5 and thus the brace C is forced downward until the point 17, Fig. 4, at the end of the cam part D is reached.

The brace C and the cam part D are loosely secured together by the slotted bar 18, Figs. 2, 3 and 4. The bar 18 is secured to the cam part D by the bolt 19 moving in the slot 20, Fig. 4, and to the brace C by the bolt 21, Figs. 2, 3 and 4. As the cam part D is rotated, the bar 18 is moved to the right and the variation in the distance between the bolts 19 and 21 is permitted by reason of the bolt 19 moving in the slot 20. When the lever 16 and the cam part D are raised, the bar 18 raises the brace C, and thereupon the brace C and the movable collar B are ready to be moved into position to perform the operation of bracing another rivet.

When the rotation of the cam part D has brought the point 17 into contact with the upper face of the brace C, further movement of the cam part D is prevented by reason

of the dog 22, Figs. 3 and 4, on the cam part D coming into contact with the dog 23 on the under face of the projection 6. When the cam part D has reached this position, continued pressure on the lever 16 further compresses the coil spring 12 and rotates the part E so that the pawl 14 engages an advanced tooth of the ratchet 8. By this means the part E is locked against backward movement and the coil spring 12 maintains the cam part D in the position in which it has been rotated and prevents the blows of the riveting tool from disengaging the same. The pawl 14 is provided, Figs. 3 and 4 with a projecting lever 24 by which the pawl is lifted from engagement with the ratchet 8 when it is desired to unlock the cam part D and return the same to non-operative position. It is obvious that the cam part D may be locked in position at any stage of its rotation and in this way allowance is made for providing a firm brace for the head of a rivet of any thickness or for variations in distance from the head of the rivet to the brace C when in non-operative position.

The brace bar A is firmly secured to the materials to be riveted together by means of securing plugs F, F, Figs. 1, 6, 7 and 9. The shaft 25, Fig. 7, of the plug F, which is inserted into the rivet hole and through the end of the brace bar A, is provided at its lower end with a lip or projection 26. The width of the shaft 25 and the projection 26 are together slightly less than the width of the rivet hole into which it is to be inserted. The shaft 25 is also provided at the upper end with two projecting parts, one of which, 27, Figs. 6, 7 and 9, is located below the end of the brace bar A and the other 28, Figs. 6, 40 7 and 9, which is located above the end of such bar A. Such projecting parts secure the bar A against up and down motion when the device is in operation. The plug F, Figs. 6, 7, 8 and 9, is also provided with a 45 plunger wedge part 29 of crescent shape which fits around the shaft 25. The width of the part 29 is the same as the width of the projecting part 26. The under face of the wedge part 29 is at an acute angle to the shaft 25 and to the surface of the material to be riveted together. Inserted into the upper face of the wedge part 29 is a plunger bar 30, Figs. 7 and 8, projecting through an orifice in the projecting part 27 and through the end of the brace bar A. Around the plunger bar 30, Fig. 7, between the part 27 and the wedge part 29 is a stiff coil spring 31 which presses downward on the part 29 and keeps the part 29 normally extended to the 55 limit of its motion. When the plug F is inserted in a rivet hole so that the projecting part 26 protrudes beyond the outer surface of the material to be riveted together, the plunger wedge part 29 is manually forced 60 downward into the rivet hole and as it

presses against the side of the rivet forces the shaft 25 to the left, Fig. 7, and forces the projecting part 26 beneath the under surface of the material to be riveted together. When such part 29 is maintained in place by the pressure of the coil spring 31 and when both plugs F, F are inserted and secured, the device is secured in position ready for operation.

The ends of the brace bar A, Fig. 5, are curved downward so as to elevate the main portion of such bar to a suitable distance above the material to be riveted so that a hot rivet may be inserted into a rivet hole in the material to be riveted together. The brace bar A is provided at its outer ends with slots 32 and 33, Fig. 1, parallel to the main part of the bar through which pass the plugs F, F. The plugs F, F may be moved back and forth in this slot until they come over convenient rivet holes into which they may be inserted and in this way considerable latitude is permitted in securing the brace bar A to the material to be riveted together.

For convenience in assembling, the end of the movable collar B is removable and is secured to the upper and lower sides by the bolts 34 and 35, Figs. 1 and 3. In this way the collar B is easily mounted on the brace bar A and as easily removed for repair.

When the brace C has been locked in position, or even before that time, the collar B is secured in position against sliding or movement along the bar A by means of the set screw 36, Figs. 1, 2 and 3.

The operation of my improved rivet brace is as follows: The brace bar A is secured in place by inserting the securing plugs F, F into convenient rivet holes and adjusting the same. A hot rivet is inserted into a proper rivet hole and the movable collar B is slid along the brace bar A until the brace part is over the head of the rivet. The lever 16 is pulled toward the operator and down. The ratchet part 8 is thus actuated and presses upon the coil spring 12 which in turn presses upon the projection 10 of the cam part D which is thus rotated. The rotation of the curved face of this cam part D and its pressure against the face 7 of the brace part C cause the brace part C to be depressed until it first comes in contact with the head of the rivet and then presses the same firmly into the rivet hole. The lever 16 is given an added pressure so as to compress the coil spring considerably. The pawl having travelled along the teeth of the ratchet is locked in the last one reached by the releasing of the lever 16. The device is now locked in operative position. When the rivet has been driven, the lever 16 is depressed slightly to relieve the pressure on the pawl and the pawl is lifted out of engagement by the lever 24 and the

lever 16 raised to normal position. The brace C is raised by means of the bar 18 being attached to it and the cam part and is raised by the lifting of the lever 16 and the rotation of the cam part. The device is now ready to be moved into position to perform the operation of bracing another rivet.

In practice various rearrangements of parts may be made without departing from the principles of my said invention, such as placing the rivet brace part immediately beneath the brace bar. In this way direct bracing is effected so that the brace bar, the rivet holes and the brace part are in a straight line and the shock of the rivet driving tool is borne directly by all parts of the device. The brace bar may be provided with a straight rod at the ends instead of plugs which may be inserted through the rivet hole. Such rod will have a slot nearly to its end which will project beyond the rivet hole. When passed through the hole it is secured in place by a wedge shaped part passed through the slot and wedged tightly in place. In this way the brace bar will be secured firmly in place.

In practice, the brace bar A is provided with several collar and brace parts so that when one rivet has been secured in place and the brace part locked in position, the operator may at once proceed to insert another rivet and lock the same in position so that when the rivet driver has finished driving the first rivet he may turn immediately to the second, third, etc. In this way the time and labor and strength of all are conserved.

Claims.

1. In a device of the class described, a brace for maintaining a rivet in place during the process of compressing the shaft of the rivet and making a head on such shaft by blows from a rivet-driving or heading-tool, comprising a brace-bar; means for securing such brace-bar to the material to be riveted together; a movable-collar mounted on such brace-bar; a rivet-brace part supported by the movable-collar; a cam-member for changing the position of and bracing the rivet-brace part; and means for locking such cam-member, and rivet-brace part in position.

2. In a device of the class described, a brace for maintaining a rivet in place during the process of compressing the shaft of the rivet, and making a head on such shaft by the action of a rivet-driving or heading-tool; and means for driving a plurality of rivets without removing the brace from the material to be riveted together comprising a brace-bar; means for securing such brace-bar to the material to be riveted together; a collar movably mounted on the brace-bar;

a rivet-brace part member carried by the 65 collar; a cam-part member for changing the position of and bracing such rivet-brace part member; and means for locking such cam-part member and rivet-brace part member in position.

3. In a device of the class described, a main-support; means for removably attaching the main-support to the stock to be riveted by securing-means coacting with holes formed in and thru the stock to be riveted 75 at one end and with the main support at the other; a secondary-support slidably mounted upon the main-support; a rivet-brace member movably carried by the secondary-support; a cam-member for forcing the 80 rivet-brace member against the rivet to be headed; and a movable lever actuated by the operator for moving the cam-member into and out of rivet-bracing position.

4. In a device of the class described, a 85 brace-bar; securing-members adjacent to the ends of the brace-bar connecting therewith at one end, and having their further ends passing thru holes formed in and thru the stock to be riveted, and removably but securely locked against accidental removal from such holes; a support slidably mounted upon the brace-bar; a rivet-brace member mounted in the support so as to move therein toward and away from the brace-bar; a 95 cam-member interposed between the sliding-support and the rivet-brace member and connecting therewith in such manner as to force them together when moved in one direction, and apart when moved in the other 100 and rivet-bracing direction; means for actuating the cam-member controlled by the operator; and a ratchet-and-pawl locking mechanism for locking the cam-member and rivet-brace member against movement when 105 in position to hold the rivet in place while being headed.

5. In a device of the class described; a brace-bar having supporting and securing end-portions extending at an angle away 110 from the central and main body or slide-portion of the brace-bar; securing-members coacting at one end with the securing end portions of the brace-bar and at the other with holes formed in and thru the stock to 115 be riveted, so as to removably but securely lock the brace-bar in position on the stock; a rivet-brace member; a support slidably mounted upon the brace-bar carrying the rivet-brace member in such manner that the 120 same may be moved therein to and from the brace-bar; mechanism for so moving the rivet-brace member; and mechanism for locking such mechanism against movement when the rivet-brace member is in the rivet- 125 bracing and holding position.

JAMES A. TAYLOR.
